UNITED STATES PATENT OFFICE.

LEONARD NELSON SALISBURY, OF FAIRMONT, WEST VIRGINIA.

GARMENT-STRETCHER.

1,137,426.

Specification of Letters Patent. Patented Apr. 27, 1915.

Application filed April 22, 1914. Serial No. 833,756.

To all whom it may concern:

Be it known that I, LEONARD NELSON SALISBURY, a citizen of the United States, residing at Fairmont, in the county of Marion and State of West Virginia, have invented certain new and useful Improvements in Garment-Stretchers, of which the following is a specification, reference being had to the accompanying drawings.

10 This invention relates to an improved garment stretcher.

The object of the invention is to provide an article of this character which shall be exceedingly simple of construction, efficient 15 and durable in use, and ready of manufacture, the parts being so constructed and assembled as to permit of their being folded to occupy but small space when not in use, and to be adjusted readily to fit a trousers leg 20 of any shape. As a matter of further specific improvement, the bars are arranged to be folded upon themselves at that portion which will come opposite the knees of the trousers, whereby the article, with the trousers thereon, may be doubled and placed 25 within a suit case.

Further and more specific details of construction will hereinafter more fully appear.

In the accompanying drawing, forming 30 a part of this specification, and in which like characters of reference designate corresponding parts: Figure 1 is a view in side elevation of a trousers stretcher formed in accordance with the present invention; Fig. 35 2 is an edge view; Fig. 3 is a view similar to Fig. 2 showing the parts folded; and Fig. 4 is a perspective detail view showing the manner in which the side members of the stretcher may be connected for folding 40 movement.

The stretcher comprises two creasing bars, each consisting of two sections 1 and 2, these sections being connected for hinged movement relative to each other intermediate of 45 their ends, the connection being secured either by the employment of an ordinary hinge, or by forming the opposed ends of the sections of each bar with hinge butts 3 of the usual construction, and held assembled by the usual pintle. The bars are 50 made of relatively thin metal, and are connected for transverse adjustment relative to

each other, by pairs of toggle links 4, of which, at present three bars are shown, although a greater number may be employed 55 if found necessary or desirable. These links are of flat metal and each is provided with a series of longitudinal orifices 5 that are designed to be engaged by a bolt or screw 6 to hold the links assembled at their upper 60 ends, the lower ends of the links being held connected with the bars by bolts 7 wing nuts 8 are mounted on the bolts whereby the links are locked against pivotal movement.

By the provision of the series of orifices 65 5, the bars may be adjusted to fit any ordinary trousers leg, and when the proper adjustment has been secured the same may be retained by the locking means connecting the lower ends of the links with the bars. 70 In order to suspend the stretcher from a hook or the like, a chain 9 is provided, the ends of which are connected with the upper terminals of the bar 5, and where it is desired to fold the stretcher to permit of its 75 being placed within a suit case, the hinges, which are disposed at the knee portion of the trousers, come into play, and permit the members of the bars being folded upon themselves. 80

While the improvements herein described are simple in character, it will be seen that they will be thoroughly efficient for the purpose designed, and will coact in the production of a novel and highly effective form of 85 garment stretcher.

Having thus described my invention, what I claim is:

A trousers stretcher comprising a pair of bars foldable intermediate of their ends 90 upon themselves, pairs of links longitudinally adjustable relative to each other, removable bolts extending through the outer ends of the links, and through the bars, and wing nuts carried by the bolts and adapted 95 to engage the links to lock the same against pivotal movement.

In testimony whereof I hereunto affix my signature in the presence of two witnesses.

LEONARD NELSON SALISBURY.
